VENTLESS DELAY ELECTRIC INITIATORS

Cecil R. L. Hall, Saltcoats, and Idwal O. Lewis, Ardrossan, Scotland, assignors to Imperial Chemical Industries Limited, a corporation of Great Britain

Application February 18, 1953, Serial No. 337,622

Claims priority, application Great Britain April 21, 1952

3 Claims. (Cl. 102—28)

The present invention is concerned with improvements in or relating to delay electric initiators and is particularly concerned with ventless short delay electric detonators.

Hitherto the delay elements in ventless short delay electric detonators have usually comprised a length of rigid metal tubing into which a powdered delay composition that yields little or no gas or vapour as it is consumed has been introduced in increments each of which is highly compressed into said length of tubing before the next increment has been introduced. In this type of delay element this incremental loading is considered essential in order to give the composition the required mechanical strength and to ensure that the packing is of a uniform density along the whole length of the column so that a rigid tube of a given length loaded with the same fuse composition will always give the same delay period. The rigid metal tube so charged with the gasless delay composition is pushed into the tubular container of the detonator in which it must fit tightly so that no annular space is left by which flame can travel from the igniting charge to the initiating charge and so that it will be secure from any sliding motion in the free space. Ventless short delay electric detonators are also produced in which the delay element is produced by filling a lead tube with a delay composition, for example, a mixture of silicon and red lead, rolling or swaging the tube to a suitable diameter to give a good fit in the ventless container and cutting off the length required. Both these types of ventless short delay electric detonators, however, when adapted to give short delay intervals, for example, of the order of 25 or 50 milliseconds have a tendency to cause ignition of an inflammable gas mixture, for example, 9% methane/air mixture, when fired freely suspended therein.

The object of the present invention is to provide a series of ventless short delay electric detonators having delay intervals between successive delay numbers, for example, of the order of 25 or 50 milliseconds which, when the ventless container consists at least essentially of copper, have the advantage that single detonators of any such practical series when fired freely suspended in an inflammable gas mixture, for example, 9% methane/air mixture, show little or no tendency to cause ignition of the gas mixture, and which when the ventless container is of aluminium or copper or copper alloys are cheaper to produce than has heretofore been possible.

It was recognised that if it were possible it would be cheaper to make ventless short delay electric detonators having a short delay composition enclosed in a lead tube of substantially reduced thickness and it was also considered that by such a reduction it might be possible to reduce the incendiary properties of a ventless short delay electric detonator if the ventless container were to consist at least essentially of copper.

It was found that improved ventless short delay electric detonators suitable for short delay firing can in fact be produced much more economically than those previously known by using as the delay element a length cut off from a fuse comprising a delay fuse composition enclosed in a lead sheath of such thickness that it is consumed or melts

2

at substantially the same rate as that at which the flame front advances along the delay element on reaction of its delay composition and a covering for said lead sheath of a thickness which will give the delay element a total thickness substantially equal to the internal diameter of the ventless container. It was also found that such ventless short delay electric detonators have the additional advantage of not causing ignition of inflammable gas mixtures, for example a 9% methane/air mixture, when fired freely suspended therein if the ventless container is of copper or a copper alloy.

According to the present invention the ventless short delay detonator comprising an electrically actuated igniting charge, an initiating charge and an interposed short delay element enclosed in a ventless container is characterised in that the sheath of said short delay element is of lead of such thinness as to be consumed or melted at substantially the same rate as that at which the flame front advances along the delay element on reaction of its delay composition and in that the sheath has a covering of a thickness to occupy the space between said sheath and container.

Preferably the ventless container consists essentially of copper or of a copper alloy rich in copper.

Preferably the covering is friable and permeable to the small amount of gas evolved during the reaction of the so-called gasless delay composition and may consist for example of paper or textiles which if desired may be provided with a coating of a thermoplastic resin.

The delay fuse composition for the core may consist of a conventional fast burning fuse composition for example a mixture of silicon and red lead in amount from 5 to 35% by weight of silicon and from 95 to 65% by weight of red lead.

The so-called gasless delay compositions produce a little gas on reaction and when these are used in a conventional manner in a lead sheath which has comparatively thick walls which are not melted or consumed until some time after the flame front has passed, the pressure developed by the gaseous products of reaction is sufficient to cause the hot slag remaining after reaction to be ejected forcibly as soon as the ventless container is disrupted. Any tendency for the hot slag to be forcibly ejected is substantially removed in the ventless short delay electric detonators of the present invention.

The lead sheath is preferably of a thickness less than the diameter of the core of the short delay element, for example, the core may be 0.050 inch in diameter and the lead sheath may be 0.015 inch thick, whereas in the conventional lead fuse delay element the diameter of the fuse is approximately 0.235 inch and the diameter of the core may be 0.1 inch.

The delay fuse element for use in the ventless short delay electric detonator of the present invention may be made by the usual methods for the production of lead fuse as for instance a lead tube of comparatively large diameter, for example 0.285 inch and internal diameter 0.177 inch filled with a delay composition can be reduced by drawing or swaging to a diameter considerably smaller, for example, to an external diameter of 0.080 inch and an internal diameter of 0.050 inch. The thin lead fuse thus produced is then covered so as to bring it to a size to fit the ventless container by for example wrapping it with paper or by spinning textiles around it and applying a finish of, for instance, a thermoplastic resin.

It is also preferred to secure the delay element in position by pressing an inverted perforated metal cup over the end thereof remote from the initiating composition instead of relying on a friction fit between the delay element and the wall of the ventless container. The use of such a cup also prevents the covering, if ignitable, from being ignited by the igniting charge.

The delay element of the ventless short delay electric detonator of the invention can be readily inserted into the container without the application of so high a pressure as to damage the structure of the delay element because the soft and somewhat compressible nature of the covering permits the necessary tight fit to be easily attained. An expansion space should be left between the end of the delay element and the igniting charge. Furthermore a small charge of supplementary, preferably gasless, igniting composition may be interposed between the end of the delay element and the initiating charge. It is also sometimes desirable to press a small charge of gasless igniting composition directly on top of the delay element, for example, by pressing it into the perforated metal cup prior to assembly in order to ensure the ignition of the delay composition from the electrically actuated igniting charge which is usually spaced from the delay element. The electrically actuated igniting charge may be an electric fusehead.

One embodiment of the invention is illustrated in the diagrammatic drawing accompanying the specification in which 1 is a copper detonator tube, 2 is a detonating explosive charge of tetryl compressed into the end of the tube, 3 is a more sensitive detonating charge functioning as the initiating charge, compressed on top of charge 2 and consists essentially of a mixture of aluminium, lead azide and lead styphnate, 4 is a lead tube, 5 is a textile covering, 6 is a polythene sheath and 7 is a delay composition. 8 and 9 are layers of gasless igniting composition consisting of silicon and red lead in the weight ratio 30 to 70, 10 is an inverted perforated metal cup pressed over the composition 9 and over the top of the delay element so as to secure it longitudinally in the tube and effectively seal off the space above this cup from the composition 9, 11 is an electric fusehead, 12 is an axially perforated sealing plug of rubber-like material crimped between the copper tube 1 and the insulated electric leading wires 13 and 13' as shown at 14 whereby there is attained a seal capable of withstanding an internal pressure greater than the maximum pressure that can be produced as a result of the combustion of the contents of the detonator tube with the exception of the detonating explosive charges 2 and 3. The space 15 between the end of the plug 12 and the inverted cup 10 is sufficient to ensure that the maximum pressure that can even temporarily be developed in the initiator by the successive consumption of the compositions of the electric fusehead 11, the igniting charge 9, the composition 7 of the delay element, together with any gases which may arise from charring of its coverings, and the igniting charge 8 will not unseal the tube.

The invention is also illustrated by the following examples in which all percentages are by weight.

Table 1

Example	Delay composition		Length of delay element, mm.	Delay time in milliseconds	
	Red lead, percent	Silicon, percent		Mean	Scatter
1	70	30	10.5	180	20
2	70	30	21.0	350	60
3	93	7	10.5	184	75
4	93	7	21.0	384	46
5	70	30	10.5	61	17
6	70	30	21.0	113	30
7	75	25	10.5	62	20

The lead delay elements in Examples 1 to 7 have an external diameter of 0.08" and internal diameter of 0.05". These are coated with paper to a diameter to fit a commercial copper detonator in which the base charge is tetryl and the upper charge is an aluminium/lead azide/lead styphnate mixture without any supplementary igniting charges top and bottom.

Table 2

Example	Delay composition		Length of delay element, mm.	Delay time in milliseconds	
	Red lead, percent	Silicon, percent		Mean	Scatter
8	70	30	10	230	20
9	70	30	25	550	30

The assemblies used in Examples 8 and 9 are the same as those of Examples 1 to 7 except that the lead fuse instead of having a paper covering has a spun jute covering and an outer coat of polythene.

A comparison of a number of types of detonator for incendiveness is carried out by exploding single detonators suspended freely in a 9% methane/air mixture using a delay composition as in Example 1 and an element of length 10.5 mm. The results are shown in Table 3. The detonators used are the same as those used in the examples except for the delay elements the structure of which is given in the table.

Table 3

	Delay element	Mean delay time	Ignitions per 10 tests
30	Incrementally loaded type brass tube of internal diameter 0.130"	100	5
	Do	257	4
	Incrementally loaded type brass tube of internal diameter 0.08"	185	10
35	Lead fuse of internal diameter 0.170" and external diameter to fit detonator tube	190	10
	Lead fuse of internal diameter 0.050" and external diameter to fit detonator tube	180	7
	Lead fuse of internal diameter 0.035" and external diameter to fit detonator tube	195	8
	Lead fuse of internal diameter 0.05" and external diameter 0.08" packed with paper to fit detonator tube	180	0
40	Lead fuse of internal diameter 0.05" and external diameter 0.08" with spun jute covering and outer covering of polythene	250	0

It will be seen from Table 3 that copper delay detonators according to the invention are non-incendive whereas copper delay detonators according to the prior art are not.

What we claim is:

1. A ventless short delay electric detonator comprising an electrically actuated igniting charge, an initiating charge and an interposed short delay element comprising a core of red lead and silicon and a lead sheath of a thickness less than the diameter of the core enclosed in a ventless container consisting essentially of copper, wherein the lead sheath of said short delay element is of such thinness as to be melted at substantially the same rate as that at which the flame front advances along the delay element on reaction of its core of delay composition and wherein the said sheath has a gas-permeable textile covering of a thickness to occupy the space between the said sheath and ventless container.
2. A ventless short delay electric detonator as claimed in claim 1 wherein the core is 0.050 inch in diameter and the lead sheath is 0.015 inch thick.
3. A ventless short delay electric detonator as claimed in claim 1 wherein the covering consists of textiles provided with a coating of a thermoplastic resin.
